UNITED STATES PATENT OFFICE

ANTON CARL REFGAARD, OF HAMBURG, GERMANY

VEHICLE HEATER

Application filed December 26, 1928, Serial No. 323,415, and in Germany December 4, 1928.

This invention relates to an apparatus for heating motor-vehicles running on land, flying in the air and floating in the water, and which are driven by an internal combustion engine, the exhaust gases of which are utilized, according to the invention, for producing hot air which is then supplied as heating medium to the compartments and seats of the motor-vehicle.

The heating apparatus consists, according to the invention, of a hollow body enclosing partly or completely the exhaust pipe or/and the silencer of the same, said hollow body forming a heating chamber surrounding the exhaust pipe or/and the silencer and communicating with the atmosphere, the air in this hollow body and the fresh air which flows in being heated by the exhaust pipe heated by the exhaust gases or by the silencer respectively and then conducted as hot air to the compartments and seats of the vehicle which are to be heated.

The hollow body forming the heating chamber is tubular, so that it can be readily placed over or on the exhaust pipe or silencer and fixed on the same to exert itself a silencing effect.

By means of suitable devices this tubular heating body can be easily mounted subsequently on existing motor-vehicles so that it is not necessary to remove the exhaust elements.

An embodiment of the invention is illustrated, by way of example, in the accompanying drawings in which:—

Fig. 1 shows in longitudinal section a heating apparatus which encloses the exhaust pipe and the silencer respectively, the exhaust pipe and silencer being shown in elevation.

Fig. 2 is a similar view as Fig. 1, the heating apparatus being arranged so that it can be mounted in an existing motor-vehicle.

Figs. 3 and 4 are cross sections through the air heater.

Figs. 5 and 6 show in end view and longitudinal section and elevation respectively an element of the heating apparatus shown in Fig. 2.

Fig. 7 shows in vertical section another

form of construction of the hollow body forming the air heater.

Fig. 8 shows diagrammatically in side elevation how the heating apparatus is arranged on a motor-car.

The hollow body 2 forming the air heating chamber 1 is preferably made of thin rust-proof sheet metal and coated on the outer or inner surface with an insulating coating 3 of asbestos plates or the like, designed to prevent radiation of heat. The hollow body 2 might be made of cast metal. The hollow body 2 is mounted on the exhaust elements of the engine so that it encloses completely or only partly the exhaust pipe 4 and the silencer 5. One or several openings for the admission of fresh air (eventually by means of supply pipes) and one or several openings for discharging the heated air are provided. The discharge openings are preferably arranged on the highest point of the hollow body 2 and the pipes or channels leading from these discharge openings to the compartments and seats of the vehicle are upwardly inclined, in order that the heated air of lighter specific gravity can flow out easily.

According to the quantity of air required a hollow air heating body 2 may be arranged on the exhaust pipe and on the silencer or on one of these two elements.

In the form of construction shown in Fig. 1 the hollow body 2 enclosing the exhaust pipe 4 is of conical-cylindrical shape, and the hollow body 2 enclosing the silencer 5 is of uniform cylindrical shape. The end 6 of this air heating body 2 is open for the admission of fresh air, the other end being closed by means of a plate 7 fixed on the exhaust pipe or silencer respectively. The open end 6 of the air heating bodies 2 may be enlarged in funnel shape in order to better catch the air, and the mouth of the air admission pipes is similarly enlarged when such admission pipes are provided.

Spacers 8 or spacing bolts 9 are used for centering and securely fixing the open end 6 of the hollow bodies 2.

As shown in Fig. 4 a number of narrow holes 10 may be arranged in the wall of the cylindrical body 2, this body being centered

and secured in position by means of wires 11 extending chord-like through the hollow body and passing through the holes 10. These wires 11 form at the same time a screen 5 against penetrating of foreign bodies. Each heating body has a discharge hole 12 for the heated air. From this discharge hole extends either a rigid tube 13 or a flexible metal tube 14, which projects through the floor 15 of the 10 vehicle into the compartment or seats to be heated.

As shown in Fig. 1 a separate channel 16 formed by a sheet metal casing 17 may be mounted on the heating body 2 and communicate with the heating chamber 1 through the discharge hole 12, the hot air from this channel 16 flowing through several narrow bores 18 into the vehicle.

The admission of hot air into the vehicle 20 can be regulated by covers 19 or throttle valves 20 in the supply pipes 13, 14 respectively.

The hollow bodies 2 constructed as shown in Fig. 2 are specially adapted to be subsequently built into existing vehicles. With this object in view the tubular body 21, which forms the hollow body 2 or the air heating chamber 1, is slit in longitudinal direction to be placed over the exhaust pipe or the 25 silencer, the joint being then closed by overlappings 22 or by means of butt straps so that the diameter of tube 21 can be adjusted as required. The overlapping ends are preferably fixed the one on the other by means of small screws 23 or by means of a wire.

In order that the end 24 of the tube 21 may be closed, it has a number of incisions which form narrow tongues 25 designed to be 40 pressed against the outer wall of the exhaust pipe 4 or of the silencer 5 by means of a clip or wire 25, so that with the aid of the insulating lining 3 this end is airtightly closed.

45 When the exhaust pipe 4 or the silencer 5 is not sufficiently distant from the bottom plate or floor or too near a wall, the air heating body may be constructed as shown in Fig. 7.

50 In this case a thick insulating layer 28 is fixed on the lower surface of the bottom plate or on the corresponding surface of the wall to protect the same against the direct action of the heat.

55 All pipes and channels designed to conduct the hot air to the point of consumption have also a heat insulating cover.

A sufficient supply of fresh air to the air heating bodies 2 may be obtained by arranging the open ends 6 of the heating bodies or the open ends of the supply pipes in the direction in which the vehicle travels, i. e. towards the front end of the same.

The fresh air flows in the direction of the 65 arrow line 29 into the air heating body, it is

heated in this body by the exhaust pipe 4 or by the silencer 5 heated by the exhaust gases from the engine, and the heated air flows then to the points, where the heating has to be carried out.

On a flying craft a separate protecting cover or screen may be provided for the heating apparatus in order that the heating process be not unfavourably influenced by the high speed.

I claim:

1. A heating apparatus for the compartments and seats of motor vehicles driven by internal combustion engines, comprising in combination a tube forming a ring-shaped heating chamber adapted to be mounted on the exhaust elements and having a longitudinal slot to adapt said tube to the desired width, tongues at one end of said slit tube formed by incisions, an insulating lining in said tube, and a clip for pressing said tongues with said insulating lining against the exhaust elements to form an airtight closing of the end of said tube.

2. A heating apparatus for the compartments and seats of motor vehicles driven by internal combustion engines, comprising in combination a tube forming a ring-shaped heating chamber adapted to be mounted on the exhaust elements and having a longitudinal slot to adapt said tube to the desired width, tongues at one end of said slit tube formed by incisions, an insulating lining in said tube, a clip for pressing said tongues with said insulating lining against the exhaust element to form an airtight closing of the end of said tube, and centering spacing and fixing means in the open end of said tube.

3. A heating apparatus for the compartments and seats of motor vehicles driven by internal combustion engines, comprising in combination with the exhaust pipe and the silencer, tubes enclosing each of said exhaust elements and closed at the rear end, and wires threaded chord-like through the open front ends of said tubes for centering said tubes and adapted to form a protecting sieve to prevent access of foreign bodies into said tubes, said sieve adapted for any width of the tube end.

In testimony whereof I affix my signature.
ANTON CARL REFSGAARD.
